CLAIM

The ornamental design for a wedge block having roller bearing for a pipe support system, as shown and described.

DESCRIPTION

FIG. 1 is a first perspective view of a wedge block having roller bearing for a pipe support system, showing my new design.

FIG. 2 is a second perspective view of the wedge block having roller bearing for a pipe support system of FIG. 1. FIG. 3 is a top plan view thereof.

FIG. 4 is a bottom view thereof.

FIG. 5 is a left side elevation view thereof.

FIG. 6 is a right side elevation view thereof.

FIG. 7 is a front plan view thereof.

FIG. 8 is a rear plan view thereof; and,

FIG. 9 is an exploded perspective view of the wedge block having roller bearing for a pipe support system of FIG. 1. The broken lines in the drawings depict portions of the wedge block having roller bearing that form no part of the claimed designs.
